United States Patent Office.

OSCAR C. FOX, OF GEORGETOWN, DISTRICT OF COLUMBIA.

Letters Patent No. 72,183, dated December 17, 1867.

IMPROVEMENT IN DRIVEN WELLS.

The Schedule referred to in these Letters Patent and making part of the same.

TO ALL WHOM IT MAY CONCERN:

Be it known that I, OSCAR C. Fox, of Georgetown, Washington county, and District of Columbia, have invented a new and improved Filter for Tubular Wells; and I do hereby declare that the following is a full and exact description thereof, reference being had to the accompanying drawings, and to the letters of reference marked thereon.

Hitherto a serious obstacle has presented itself where tubular wells were to be sunk in fine gravel and quicksand, to wit, the difficulty in presenting a large amount of available surface of screen to the body of water to be filtered from the sand, so that the water could literally soak or filter through into the tube of the well to supply the pump above; also, in so arranging the parts that the screen used is firmly located and protected from injury or wear by the action of the water or the earth upon it.

The nature of my invention consists in constructing a filter of fine wire cloth, so arranged and supported by wire cloth of a coarser texture, that the water has free ingress through every portion of its surface, and, what is very important, the finest and most delicate fabric of wire gauze can be employed, if necessary, with entire firmness and durability.

To enable others skilled in the art to make and use my invention, I will proceed to describe its construction and operation.

A represents a coil or cylinder of fine wire gauze, and is supported by the concentric cylinders N and P, composed of coarse wire cloth, of four and sixteen meshes to the inch, respectively, the coil A being sixty meshes to the inch, or finer. For a heavier coil I use Nos. 4, 8, 16, 30, and 60, or finer, or as near these numbers as practicable, and I sometimes protect the wire gauze further by an exterior coil of No. 8 wire cloth. When this cylinder of woven wire has been formed properly upon a round bar, then drawn off, it will be firm and unyielding like a solid metallic tube, and capable of sustaining a heavy pressure; and the pulsations of the water, resulting from the pump-stroke, cannot fret or wear through the fine wire gauze, as in cases where it is imperfectly supported by a spiral wire or spring, or similar device. B represents a common iron or other metal tube, into which the cylinder of wire cloth or the filter-tube is introduced. C is a drill-shaped point, firmly attached to the filter-tube, and is intended to remain stationary in the earth while the tube B is drawn up, thus exposing the wire gauze A to contact with the sand and water. K represents a small hole plugged with a roll of wire gauze, and communicating with the inside of the tube. I pour in small quantities of water occasionally from the top of the tube, and this outlet K permits the water to escape gradually, and as the drill-point is rotated (in dry hard clay especially) the moisture softens the soil, and renders it easy of penetration. The hole, it will be perceived, is located in the rear of the advancing edge of the point as it turns, thus keeping clear of sand and obstructions.

It has been found, where a spiral or other devices have been employed to support the fine wire cloth, that a very fine quality of wire cloth could not be employed, and that in a short time the wire cloth used is worn through, and rendered useless by coming in contact with the outer and inner supports, and being subject, constantly, to the intermittent action of the water. All these troubles my improvement is intended to remove, and to present the greatest area of wire screen to the direct action of the water, as it will be perceived that I can draw up the tube B to the distance of twenty inches or two feet, or any distance, according to the length of the filter-tube, and still, the wire gauze being supported at every point, is firm, and like a solid metallic tube.

I employ, for the supporting fabric, galvanized iron, and for the fine fabric brass or tinned material. For the well-tube I use wrought-iron pipe. The filter-tube may be attached to the point C by screwing it on to a rod projecting upwards, and previously welded in with the point, the coil having been also provided with a socket, soldered or otherwise made fast into the lower end, or a cast or malleable-iron point, may be used, upon which a neck is turned which fits up into the lower end of the well-tube, and to the top of which the filter-tube is attached. At M is shown a pin or projection, which fits into the slot at I, holding the point C to its position, fitting, as it does, closely to the tube B, until the desired depth is reached, when the tube B is turned backwards slightly, detached from the point, and drawn up, to expose the filter-tube to the water and earth, as seen in the figure. The tube B is kept from entirely leaving the wire cloth A by a thin ring or projection, L, which engages with another ring attached to the upper end of the coil A.

In constructing a well in soft, easy soil, I use a common iron pipe, of one or one and a fourth inch bore, driving it into the earth with a sledge, or by any convenient method; but when the soil is hard, and the water at a considerable depth, I employ a solid rod of iron, which I finally withdraw, and insert the pipe to which the pump is attached. In hard soil, to facilitate the sinking, I employ weights, which I load on to a hammock or platform, attached to the pipe by a set of chains, and a sliding socket, the latter being furnished with set-screws or some device, so that it can be made fast to any point on the pipe. Thus when the pipe, so loaded, is turned in the ground, this weight tends to force the point of the pipe into the earth like a drill. For turning the pipe I use a large pair of pipe-tongs, with a long handle attached, and it will be found of advantage to give the pipe a rotary motion, in all cases, whatever method of sinking may be adopted, the most common mode being to drive and rotate at the same time, or alternately, at short intervals, especially when the solid rod is employed.

I am aware that wire gauze has been used as a filtering medium in well-tubes, and that tubes so provided have been formed of strong perpendicular wires or rods. By my invention the tube is formed of woven wire, strong enough to resist the vertical and lateral pressure to which it may be exposed. Yet from the strength imparted by the transverse wires and their interlacing, greater efficiency may be obtained from lighter materials, and I apply wire gauze as a filter inside or outside of this coarse and strong woven-wire tube.

Having described my invention, what I claim, and desire to secure by Letters Patent, is—

A well-tube constructed wholly of woven wire of different textures, as shown, combined and arranged with a drill-point, having a drip through its body, all substantially as and for the purposes described.

OSCAR C. FOX.
